FLASHLIGHT

Anthony J. Desimone, Lyndhurst, N. J., assignor
to Bright Star Battery Company, Clifton, N. J.,
a corporation of New York

Application January 23, 1939, Serial No. 252,244

4 Claims. (Cl. 240—10.6)

This invention relates to flashlights and has as an object a provision in a flashlight of simple and effective means for interrupting current flow through the bulb filament in the event of breakage of the bulb.

Such an arrangement is desirable for flashlights used in locations where there is a possibility of the atmosphere containing explosive fumes which might become ignited and contact a hot filament. With the arrangement of the present invention, breakage of the bulb results in interruption of current flow and so precludes the possibility of the ignition of explosive fumes should any be in the immediate vicinity of the bulb. Furthermore, the arrangement is such that not only is the current flow interrupted but also the filament is broken, thus providing an additional measure of protection.

A further object of the invention is the provision in a flashlight of the character above described of shock absorbing contact means for establishing electrical connection between the battery and the bulb. Such an arrangement minimizes the possibility of injury to the bulb should the flashlight be dropped or subjected to a severe blow.

Other objects, novel features and advantages of this invention will become apparent from the following specification and accompanying drawings, wherein:

Fig. 1 is a side elevation partly in section of a flashlight embodying the invention;

Fig. 2 is an enlarged fragmentary longitudinal section;

Fig. 3 is an enlarged fragmentary elevation partially broken away;

Fig. 4 is a fragmentary perspective view of the flashlight tube;

Fig. 5 is a perspective view of the bulb holder; and

Figs. 6 and 7 are fragmentary views generally similar to Fig. 2 illustrating the different types of shock absorbers.

The flashlight comprises a tube composed of molded plastic material such, for example, as cellulose acetate and is provided at either end with threads for the attachment to the tube of the base cap 11 and the head 12. At the upper end of the tube is an inturned integral flange 13, the inner surface of which is engaged by the base of a metal cup 14, said base having a central aperture. An insulating washer 15 is arranged between the cap and a rigid yoke member 16 and rivets 17 passing successively through the yoke member, the insulating washer, the base of

the cup and the flange bind such elements together in assembled relation.

5 A socket 18 has a flange 19 which engages the outer surface of the cup 14 and is fastened thereto by rivets 20. The socket has a smooth bore and its exterior surface is screw threaded at 21. A resilient strip 22 spans the yoke member 16 and supports a center contact 23 for engagement by the center contact of a bulb 24 mounted 10 in the socket 18. A helical spring 25 is supported by the insulating washer 15 within the socket 18 for engagement by the base of the bulb 24.

A screw-threaded collar 26 is supported by the 15 socket 18 and is provided with a pair of crossed wire loops 27 which engage the bulb 24 to hold the latter with its center terminal engaging the contact 23, the spring 25 being under compression and forcing the bulb 24 into contact with the loops.

20 A metal strip 28 extends longitudinally of the tube 10 and is connected by attachment means 29 with a button 30 exterior of the tube, a slot 31 being provided in the tube for permitting such connection and for permitting reciprocation of 25 the strip 28 by the button 30 relative to the tube 10. As shown in Fig. 1, the upper end of the strip 28 in one position of the button 30 engages the cup 14 to close the bulb circuit but when retracted from such position moves out of contact 30 with the cup to open the bulb circuit.

The arrangement of yoke 16, spring 22 and contact 23 constitutes a shock absorber for cushioning the bulb against shocks caused by blows striking the tube or by dropping of the flashlight. The 35 spring 25 serves to project the bulb 24 outwardly to break the contact between its center terminal and the contact 23 in the event of breakage of the bulb, thereby discontinuing current flow through the filament. Also, the outward movement of the broken bulb brings the filament into contact with one of the loops 27 thereby breaking the filament and providing additional prevention against ignition of explosive fumes, should any be present. The position assumed by the bulb in the 40 event of breakage is clearly shown in Fig. 3.

The head 12 carries a reflector 32 and lens 33 held in assembled relation to the head by the lens ring 34. The loops 27 pass through the aperture in the reflector, thereby permitting removal of the 50 head 12 without disturbing the collar 26. After removal of the head, the collar 26 may be unscrewed from the socket 18 to permit the removal of a broken bulb and the insertion of a new bulb.

55 In the modification disclosed in Fig. 6, the

aperture in the flange 13 is countersunk from the inside and the metal cup is offset inwardly at 14a into the countersunk portion. The flange 19 of the socket 18 fits into the offset portion 14a. A button 35 of insulating material is supported from the flange 13 by rivets 17 and has a central recess 36 which is countersunk at its upper end to receive an insulating washer 37 which engages the bottom of the socket 18. A rivet 38 extends through the button 13 into the recess 36 and is electrically connected to a spring 39 which engages the contact member 23 to press the same into engaging relation to the center terminal of the bulb 24. The exterior surface of the socket 18 is threaded as previously described for the purpose of receiving the collar 26.

The modification illustrated in Fig. 7 differs from that of Fig. 2 in that sleeve 40 is supported by the yoke 16 and the contact 23 is held in position to engage the center terminal of the bulb 24 through the medium of a helical spring 41 interposed between contact 23 and the yoke 16.

I claim:

1. A flashlight comprising a casing of insulating material having an inturned flange at one end, a metal cup having an opening in its bottom arranged in said casing with the cup bottom contacting the inner surface of said flange, an apertured disk of insulating material within said cup closing said opening, a socket attached to said cup bottom and arranged in the space defined by the inner edge of said flange, said socket having a smooth inner surface and a screw-threaded outer surface, a center contact for said socket extending through said disk aperture and resiliently supported from said flange and being insulated by said disk from said cup and socket, a spring in said socket for engagement by the base of a bulb in said socket and having one end engaging said insulated disk, a screw-threaded collar on said socket, and a loop carried by said collar for holding said bulb with its center terminal in engagement with said center contact.

2. A flashlight comprising a casing of insulating material having an inturned flange at one end, a metal cup having an opening in its bottom arranged in said casing with the cup bottom contacting the inner surface of said flange, an apertured disk of insulating material within said cup closing said opening, a socket attached to said cup bottom and arranged in the space de-

fined by the inner edge of said flange, said socket having a smooth inner surface and a screw-threaded outer surface, a rigid yoke supported by said flange within said cup and insulated therefrom by said insulating disk, a resilient strip spanning said yoke and supported at each end thereby, a center contact for said socket carried by said strip and extending through the aperture in said disk, a spring in said socket for engagement by the base of a bulb in said socket and having one end engaging said resilient disk, a screw-threaded collar on said socket, and a loop carried by said collar for holding said bulb with its center terminal engaging said center contact.

3. A flashlight comprising a casing of insulating material having an inturned flange, a metal cup having its bottom contacting the inner surface of the flange, a button of insulating material supported by said flange in contact with said cup, a socket carried by said button in contact with said cup, a contact member slidably supported by said button for engagement with the center contact of a bulb mounted in said socket, resilient means tending to urge said contact into said socket, a stationary contact exterior of said button electrically connected to said slidable contact, a screw thread on the outer surface of said socket, a spring in said socket for engagement by the base of the bulb in said socket, a screw-threaded collar on said socket and a loop carried by said collar for holding said bulb with its center terminal in engagement with said center contact.

4. A flashlight comprising a casing of insulating material having an inturned flange, a metal cup having its bottom contacting the inner surface of said flange, a rigid yoke supported by said flange and insulated from said cup, a helical spring supported by said yoke, a center contact supported by said spring, a socket carried by the bottom of said cup and insulated from said center contact, a screw thread on the outer surface of said socket, a spring in said socket for engagement by the base of a bulb in said socket, a screw-threaded collar on said socket and a loop carried by said collar for holding said bulb with its center terminal in engagement with said center contact.
